DESIGN FOR A DECANTER BOTTLE

Charles W. Neusbaum and Charles E. Marchino, Vincennes, Ind., assignors to Vincennes Packing Corporation, Vincennes, Ind., a corporation

Application June 22, 1940, Serial No. 93,200

Term of patent 14 years

To all whom it may concern:

Be it known that we, Charles W. Neusbaum and Charles E. Marchino, citizens of the United States and residents of Vincennes, county of Knox and State of Indiana, have invented a new, original, and ornamental Design for a Decanter Bottle, of which the following is a specification, reference being had to the accompanying drawing, forming part thereof.

In the drawing,

Fig. 1 is an elevational view of the decanter bottle showing our new design, and Fig. 2 is a top plan view thereof.

The dominant features of our design reside in the portions shown in solid lines.

We claim:

The ornamental design for a decanter bottle, substantially as shown and described.

CHARLES W. NEUSBAUM.

CHARLES E. MARCHINO.
